UNITED STATES PATENT OFFICE

105,832

DESIGN FOR A TUCKED EMBROIDERED TEXTILE FABRIC

Benjamin Beidner, New York, N. Y.

Application July 15, 1937, Serial No. 70,458

Term of patent 3½ years

To all whom it may concern:

Be it known that I, Benjamin Beidner, a citizen of the United States of America, residing in Manhattan, county of New York, and State of New York, have invented a new, original, and ornamental Design for a Tucked Embroidered Textile Fabric, of which the following is a specification, reference being had to the accompanying drawing, forming part thereof, wherein, the figure is a plan view of a piece of tucked embroidered textile fabric showing one complete design unit.

I claim:

The ornamental design for a tucked embroidered textile fabric, substantially as shown and described.

BENJAMIN BEIDNER.
